SCREEN AND STORM SASH HANGER

Joseph H. Meredith, Springfield, Mo.

Application April 4, 1938, Serial No. 199,982

2 Claims. (Cl. 16—172)

This invention relates to hangers for screens and storm sash and has for the primary object the provision of an efficient and inexpensive device of this character which may be installed by anyone and which will permit a screen or storm sash to have a hinging movement and to be easily and quickly removed and replaced on a window frame when desired.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a front elevation showing hangers constructed in accordance with my invention securing a screen to a window frame.

Figure 2 is a fragmentary sectional view taken on the line 2—2 of Figure 1.

Figure 3 is a fragmentary front elevation showing my invention connecting a half screen to a window frame.

Figure 4 is a fragmentary front elevation showing my invention connecting the storm sash to a window frame.

Figure 5 is a fragmentary front elevation showing my invention securing a full length screen to a window frame with the parts of my invention reversely arranged to that shown in Figure 1.

Figure 6 is a fragmentary front elevation showing the parts of my invention reversely arranged to that shown in Figure 3.

Figure 7 is a fragmentary front elevation showing the attaching plate as being interposed between the screen and the window frame.

Figure 8 is a fragmentary front elevation showing parts of my invention reversely arranged to that shown in Figure 5.

Referring in detail to the drawing, the numeral 1 indicates a window frame, 2 a storm sash, 3 a screen of the full length type and 4 a screen of the half screen type. The purpose of illustrating the different forms of screen in the storm sash is to show clearly how these devices can be easily mounted on the window frame by the employment of hangers 5 forming the subject matter of the present invention.

Each hanger 5 consists of an attaching plate 6 apertured to receive screws or like fasteners 7. An arm 8 is formed on one edge of the plate 6 adjacent one end of the latter and said arm includes angularly related portions 9 and 10, the portion 10 having a slot 11. The portion 9 of the

arm 8 may extend from the plate 6 at either a substantially 60 degree angle or a 90 degree angle or if desired, the user of this device can bend the arm 8 to extend at any desired angle from the attaching plate to meet with building constructions.

The present invention further consists of an attaching plate 12 apertured to receive screws or like fasteners 13 and has formed on one end a hook 14 to extend through the slot 11 in the arm 8.

In use, a pair of hangers is employed for the mounting of either a screen or storm sash and the attaching plates 6 of the hangers may be secured to the upper corners of the screens, as shown in Figures 1 and 3, or to the upper corners of the storm sash, as shown in Figure 4. The arms may be arranged to extend either inwardly or outwardly, as shown in Figures 1, 3, 4, 5, 6 and 7. The attaching plates 6 are secured to the window frame and with the hooks extending through the slots 11 so that the hanger 5 will hold screens or the storm sash efficiently secured to the window frame to prevent the entrance of insects or prevent wind from getting behind the frames of the sash or screens and disturbing the location of the frames of said sash or screens with respect to the window frame. Window frames used in conjunction with brick buildings are sometimes ribbed upon their outer faces and thereby would interfere with the application of the hangers to said faces. The hangers may be secured to such frames, as suggested in Figure 7 with the attaching plate 6 secured to the inner edge of the window frame 1, and the portion 9 extending inwardly and away from the said frame and having the integrally formed end 10 lying in a plane parallel to the plane of the screen 3. The attaching plates 12 are secured to the screen adjacent the top edge, with the hook portion received within the elongated slot 11 in the end 10. The attaching plates 6 of the hangers when secured to the corners of the screen frames will reinforce such corners and prevent separation of the members of the frame of the screen.

Having described the invention, I claim:

1. A hanger comprising companion sections; one of said sections having a flat base of substantially rectangular formation in plan, a transversely extending arm portion integrally attached to one of the longitudinal edges of the base adjacent the top edge thereof, the extremity of the arm having an elongated slot and the portion of the arm immediately laterally of the said base extending angularly upwardly and outwardly

from the base and being bent to position the extremity thereof in a plane parallel with and laterally of the base above the said top edge; and the other of the said sections adapted to be positioned laterally of the base portion of the first-mentioned section below the extremity of the arm and being of substantially triangular formation in plan and having the apex thereof rolled upwardly to constitute a hook adapted to register with and to be received by the elongated slot in the extremity of the arm of the said first-mentioned section.

2. A hanger comprising companion sections adapted to be secured to a window frame and sash respectively; one of said sections including an elongated substantially rectangular base portion having spaced apertures to receive attaching screws, a transverse extension attached to one of the longitudinal edges of the base, said

extension having an elongated slot in its free end and with the end adjacent the base being bent angularly relative to both the extremities thereof and the said base to position the base in a plane at right angles to a plane containing the extremity, the angularly disposed portion of the extension extending angularly upwardly at one side of the base in a manner to position the said extremity laterally and above the base; the other of the sections being of substantially triangular formation in plan and with the base portion provided with spaced apertures to receive attaching screws and with the apex thereof rolled upwardly to comprise a hook adapted to register with and to be received by the elongated slot in the transverse extension of the said first-mentioned section.

JOSEPH H. MEREDITH.
